(57) **CLAIM**

The ornamental design for a rechargeable controller for string lights, as shown and described.

DESCRIPTION

FIG. 1 is a front elevation view of a rechargeable controller for string lights, showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a top, front, right side perspective view thereof;

FIG. 8 is a bottom, front, left side perspective view thereof; and,

FIG. 9 is a top, front, right side perspective view of the rechargeable controller for string lights of FIG. 1, shown in a condition of use.

The broken lines in the drawings depict portions of the rechargeable controller for string lights that form no part of the claimed design. In FIG. 9, the broken lines showing a cable depict environmental subject matter only, and form no part of the claimed design.

1 Claim, 9 Drawing Sheets
